UNITED STATES PATENT OFFICE.

GEORGE D. MOULTON, OF DENISON, TEXAS.

DESIGN FOR A HANDLE FOR SAFETY RAZORS.

Application filed June 5, 1924. Serial No. 9,807. Term of patent 14 years.

To all whom it may concern:

Be it known that I, GEORGE D. MOULTON, a citizen of the United States, residing at Denison, in the county of Grayson and State of Texas, have invented a new, original, and ornamental Design for Handles for Safety Razors, of which the following is a specification, reference being had to the accompanying drawing, forming part thereof.

The figure is a front view of a handle for safety razors showing my new design.

I claim:

The ornamental design for a handle for safety razors, as shown.

GEORGE D. MOULTON.
